ATTORNEY

UNITED STATES PATENT OFFICE.

WILLIAM H. TAPPER, OF ALDA, ASSIGNOR OF ONE-HALF TO ROY H. STUART, OF HALL COUNTY, NEBRASKA.

WEATHER-STRIP.

SPECIFICATION forming part of Letters Patent No. 247,786, dated October 4, 1881.

Application filed April 11, 1881. (No model.)

To all whom it may concern:

Be it known that I, WILLIAM H. TAPPER, of Alda, in the county of Hall and State of Nebraska, have invented certain new and useful 5 Improvements in Weather-Strips; and I do hereby declare that the following is a full, clear, and exact description of the invention, which will enable others skilled in the art to which it appertains to make and use the same, 10 reference being had to the accompanying drawings, which form a part of this specification.

Figure 1 is a rear view, and Fig. 2 is a vertical sectional view, of my improved weather-strip.

15 Similar letters of reference indicate corresponding parts in both figures.

This invention relates to weather-strips for doors, &c.; and it consists in certain improvements in the construction of the same, which 20 will be hereinafter more fully described, and particularly pointed out in the claim.

In the drawings hereto annexed, A represents a molding to be secured to the lower edge of a door by screws or in any other suitable manner, and provided upon its inner side 25 with a recess, B, in which bearings are provided for a longitudinally-sliding rod or arm, C, forced in an outward direction by a coiled spring, D, and having preferably its outer and projecting end formed with a beveled end, E.

The rod or arm C is provided at or near its center with a pivoted tongue or lever, F, fitted upon the upper side of a horizontal vertically-sliding bar, G, provided in its lower edge with 35 a longitudinal groove, H, in which a strip, I, of rubber cloth or any other suitable flexible material, is fitted, as shown.

The bar G is provided with a bail, J, in which a flat spring, K, is fitted, as shown, the ends 40 of the said flat spring being adjusted over studs L in the recess B, so as to force or hold the said bar G in a raised position.

From the foregoing description, taken in connection with the drawings hereto annexed, the 45 operation and advantages of my invention will be readily understood. The device is to be secured to the lower edge of the door. When

the door is closed the projecting end of the rod C, striking against the jamb, forces the said rod in an inward direction, thus causing the lever 50 F to force the weather strip down against the threshold, so as to exclude wind and moisture. When the door is opened the coiled spring D forces the rod C in an outward direction, thus permitting the weather-strip to be raised and 55 the door to be easily opened, especially when, as is frequently the case, the lever or link F has assumed a vertical position, bearing directly down upon the flat spring K, in which case nothing but force laterally exerted against 60 the said lever F will cause it to tilt and raise the weather-strip. The spring D is therefore a very important adjunct to my invention.

I am aware of the fact that automatic devices operating the weather-strip by the closing of the door are not new. Most forms heretofore used have, however, been objectionable for various reasons. I am aware of the patents to Fisher, No. 35,224; Gowen, No. 237,516, and Bennett, No. 167,820, and I claim nothing 70 therein shown; but,

Having thus described my invention, I claim and desire to secure by Letters Patent of the United States—

As an improvement in weather-strips, the 75 combination, with the molding A, having recess B, provided with lugs L L, of the longitudinally-sliding rod C, having beveled end E and lever F, near its center, forced in an outward direction by a coiled spring, D, at its end opposite the beveled portion, and the longitudinal bar G at the bottom, having flexible strip I and bail J on its upper side, in which bail a flat curved spring, K, is fitted with its ends 80 adjusted over studs or lugs L, all combined and operating substantially as and for the purpose herein shown and specified.

In testimony that I claim the foregoing as my own I have hereto affixed my signature in presence of two witnesses.

WILLIAM H. TAPPER.
